Des. 227,303

Patented June 12, 1973

227,303

SIGHTING DEVICE FOR FIREARMS

William F. Steck III, El Paso, Tex., assignor to
W. R. Weaver Company

Filed Mar. 17, 1971, Ser. No. 125,464

Term of patent 14 years

Int. Cl. D16—06

U.S. Cl. D57—1 E

FIG. 2

FIG. 1

FIG. 3

FIG. 4

FIG. 1 is an elevational side view of one side of a sighting device for firearms embodying my new design;

FIG. 2 is a top plan view of a sighting device of FIG. 1;

FIG. 3 is an end view of a sighting device as viewed from the right hand end of FIG. 1; and

FIG. 4 is an end view of the sighting device as viewed from the left hand side of FIG. 1.

I claim:

The ornamental design for a sighting device for firearms, as shown and described.
